WALL PLAQUE

Susan Kuller Traub, 9121 Market Lane,
Greenbelt, Md. 20770

Filed Sept. 2, 1966, Ser. No. 3,712

Term of patent 7 years

(Cl. D29—23)

FIG. 1.

FIG. 2.

FIG. 3.

FIG. 1 is a front elevation of a wall plaque showing my new design;

FIG. 2 is a cross section taken on the line 2—2 of FIG. 1; and

FIG. 3 is a right side elevation thereof, the left side presents a mirror image thereof.

The back of the plaque is plain and unornamented.

The characteristic features of my design reside in the combination on the wall plaque disclosed of the representation of a circus car having a pictorial representation of a caged animal thereon, the cage bars being in the form of superimposed yarn and the entire plaque being surrounded by matching ball type fringe, all as shown.

I claim:

The ornamental design for a wall plaque, as shown and described.
